METHOD AND APPARATUS FOR FIBER COLLECTION

Edison H. Novotny, Monmouth Junction, and Lee M. Hedges, Somerville, N. J., assignors to Johns-Manville Corporation, New York, N. Y., a corporation of New York

Application September 24, 1949, Serial No. 117,559

13 Claims. (Cl. 154—101)

The instant invention relates to an improved method and apparatus for collecting fibers in interfelted relationship, and more particularly, to a method and apparatus adapted to provide a uniform, lofty, lightweight felt of previously opened, or partially opened, fibers. The invention relates especially to the felting of relatively fragile, brittle fibers, such as mineral wool fibers, but is also suitable for use with mixtures of such fibers and other fibers, or with other fibers alone.

A principal object of the invention is the provision of a method and apparatus for the collection of fibers in interfelted relationship which will produce a low-density, lofty and uniform felt.

Another object of the invention is the provision of such method and apparatus in which the fibers are collected from an air suspension thereof in a zone of substantially zero static pressure, whereby the fibers are not compressed or disturbed after felt formation. Hence, a lightweight uniform product is obtained.

A further object of the invention is the provision of a method and apparatus of the kind referred to including a fiber opening device which discharges the opened fibers into a gaseous current flowing to the collection zone.

A still further object of the invention is the provision of such method which permits the inclusion of an adhesive material in the felt to provide the desired handleability of the uncured felt. Also, the method provides for the distribution of an unset binder, where desired, within the felt, the binder being set in later product finishing operations.

The foregoing objects are attained by our invention which resides, briefly stated, in an apparatus and method involving a fiber collection chamber or tower to which the fibers are delivered in an airstream, fiber opening means within the tower adjacent the entrance port for the fibers, a fiber collecting means, suitably an air-pervious conveyor, and means for suspending the fibers in an air current moving toward the conveyor. A zone of substantially zero static pressure is maintained at and adjacent the surface of the conveyor whereby the felting takes place without substantial agitation or compression. Means are provided for introducing a binder in a finely-divided state, suitably a powdered resin or the like, at a convenient location prior to the felting of the fibers. Also, means are provided for introducing, preferably by spraying, an adhesive material into the suspension of fibers before felting, to impart handleability to the felt before the binder has been set. The apparatus and method are of particular advantage when used with relatively brittle fibers, such as mineral wool fibers, or mixtures thereof with conventional textile fibers.

Our invention will be more fully understood and further objects and advantages thereof will become apparent when reference is made to the more detailed description of a preferred embodiment of the invention which is to follow and to the accompanying drawings in which:

Fig. 1 is a diagrammatic, elevational view with parts

2

in section, illustrating an apparatus embodying the invention and for carrying out the method thereof;

Fig. 2 is a sectional view, taken on the line 2—2 of Fig. 1; and,

Fig. 3 is a sectional view, taken on the line 3—3 of Fig. 1.

Referring now to the drawings, there is shown a felting or collection chamber or tower 10 including an upper section 12 of restricted cross-section (see Figs. 1 and 2) and a lower section 14 flaring outwardly from the upper section (see Figs. 1 and 3). The floor of the collection chamber comprising an endless conveyor 16 driven in the direction indicated by the arrow by suitable means (not shown). Conveyor 16 is of wire mesh or other suitable openwork or foraminous, air-pervious construction, to permit the movement of air therethrough. A suction box 18 is located below the upper reach of the conveyor, the suction box being connected to the exhaust side of a blower 20 by duct 22.

20 A duct 24 leads from some suitable source of supply of preferably cleaned and opened, or partially opened fibers, and connects into the collection chamber 10 at the upper end of section 12 and adjacent one of its side walls. Cooperating card rolls 26 driven in the directions indicated by the arrows, are located within the upper section 12, the card rolls closing off a portion of the cross-sectional area of the section to the passage of the fibers, except between the card rolls. Substantially the remainder of the area is closed off to the passage of fibers by a cylinder 28 having a peripheral wall composed of wire mesh screen, perforated metal, or of other openwork construction. The cylinder is driven in the direction indicated by the arrow.

30 Apparatus may be provided of any suitable type for receiving the felt formed on conveyor 16. In the drawing this apparatus is shown as a lapper 30 of conventional design adapted to lay the felt or web in a plurality of successive folds laterally onto a continuously driven conveyor 32 extending at right angles to conveyor 16 and lapper conveyor 30.

35 The drive for the several rolls, conveyors and other moving parts have not been shown, but it will be appreciated that these may be of any conventional type to permit relative speed control of the different operations.

40 Means are provided for applying both binders and adhesives to the fibers prior to their collection. The binder applicator may be located to introduce the binder at any suitable point prior to the collection of the fibers and, as illustrated, consists of a binder supply line 34 connected to any suitable supply (not shown) of a dry powdered binder and having a delivery end or nozzle substantially at the point where the fibers enter the collection chamber, to direct the binder in an airstream onto the fibers as they pass to the card rolls. However, the binder may be introduced at an earlier point in conduit 24 or below the card rolls, if desired. An adhesive is preferably applied to the fibers in addition to the binder, and for this purpose a sprayhead 36 connected by a line 38 to any suitable adhesive supply (not shown) is mounted adjacent a wall of the collection chamber and substantially above the floor thereof, and is pointed in a direction to project a fine spray of adhesive into the suspension of fibers below the card rolls.

45 In the operation of the apparatus described above and in carrying out the method of the instant invention, opened or partially opened fibers are carried by an airstream from a suitable supply thereof (not shown) through duct 24, and introduced into the collection chamber in the upper end of section 12 of the collection chamber. The fibers employed may be of any conventional type, as previously mentioned, but the apparatus

and method are particularly adapted for the felting of relatively fragile, brittle fibers, such as mineral wool fibers, or such fibers intermixed with fibers of other types. As stated, the fibers introduced to the collection chamber have previously been cleaned and at least partially opened in any suitable way, the fiber cleaning and opening apparatus shown in our co-pending application, filed of even date herewith, being preferred for this purpose.

The fibers entering the collection chamber are deposited onto card rolls 84 and carried therebetween for a final opening and fiber individualizing operation. The air entering with the fibers passes through the air-pervious walls of cylinder 28 and into the collection chamber. The air flows past and below the card rolls at a reduced velocity, due to the greater cross-sectional area of the collection chamber as compared to the conduit 24. The air current, decreasing in velocity as it approaches conveyor 16, because of the outward flare of section 14, carries the fibers onto the conveyor. Blower 20 is operated by controlling its speed or the volume of air withdrawn by it in a manner such that suction is set up in suction box 18 to create a negative pressure of a value sufficient to only overcome the resistance to the passage of air through the mass of fibers on the conveyor. In this way a zone of practically zero static pressure is provided at and above the conveyor which performs several important functions. It eliminates the necessity of a seal roll at the exit port from the collection chamber as the air pressures inside and outside the chamber are substantially the same. Also, and of primary importance, the felted web is not compressed or disturbed after it is formed and, hence, is of low-density and in a lofty state. Furthermore, very uniform felting is obtained.

Where the finished product is to contain a binder, the binder material in an unset state, preferably a powdered resin, and either of a thermoplastic or thermosetting type, for example a resin such as urea-formaldehyde, phenol-formaldehyde, or other resinous material is introduced to the fibers through line 34, the powdered material becoming intimately intermixed with the fibers as they pass between the carding rolls and flow downwardly onto conveyor 16. In the preferred practice, an adhesive material is applied to the fibers whether or not a binder is to be employed, the adhesive having the function of adhering the fibers of the felt sufficiently to enable the lightweight felted web to be lapped and/or subjected to other finishing operations prior to the setting of the binder. The adhesive, which should be a type that will effect cohesion of the fibers but not to be so sticky as to cause undue fouling of the chamber walls, is introduced through line 38 to sprayhead 36 and sprayed into the suspension of fibers as they pass to the conveyor. A preferred adhesive is a glycerine solution, for example, a 10% glycerine water solution.

Conveyor 16 may be driven at a slow speed to build up a layer thereon of the required thickness for the final product. However, it is usually found preferable to form a relatively thin, lofty felt on the conveyor and convert the same into a blanket of the desired thickness by a lapping operation. For this purpose the layer collected on conveyor 16 is transferred to the lapper conveyor and laid in successive folds transversely of conveyor 32. In either case, that is whether the layer is built up to the desired thickness on conveyor 16, or whether it is lapped to provide a blanket of the desired thickness, the blanket may be subjected to any usual or conventional binder setting and other finishing operations to convert it into bonded batts or blankets, or into loose wool, nodulated wool, and the like.

The above-described method and apparatus are versatile in operation and may be used with extremely brittle fibers without undue fiber breakage. They may be employed for the production of felts containing mixtures of fibers or fibers of different types may be successively handled. Irrespective of the type of fibers employed,

the products obtained are low in density, light in weight, lofty and of uniform structure.

Having thus described our invention in rather full detail, it will be understood that these details need not be strictly adhered to and that various changes and modifications may suggest themselves to one skilled in the art, all falling within the scope of the invention as defined by the subjoined claims.

What we claim is:

1. A method of collecting opened fibers comprising, delivering the fibers in an airstream to a collection chamber at a point above a collection zone thereof, introducing a finely-divided binding material to said fibers, subjecting said fibers and binder to a fiber opening and binder distributing operation, discharging the opened fibers with binder into an air current moving toward said collection zone to form a suspension therein, spraying an adhesive material into said suspension, and collecting the fibers from said suspension in interfelted relationship in said zone.

2. A method of collecting opened fibers comprising, delivering the fibers in an airstream to a collection chamber at a point above a collection zone thereof, introducing a finely-divided binding material to said fibers, subjecting said fibers and binder to a fiber opening and binder distributing operation, discharging the opened fibers with binder into an air current moving toward said collection zone to form a suspension therein, spraying an adhesive material into said suspension, maintaining substantially zero static pressure in said zone, and collecting the fibers from said suspension in interfelted relationship in said zone.

3. An apparatus for collecting opened fibers in interfelted relationship comprising, a collection chamber, fiber collecting means in said chamber, means for conducting an airstream carrying fibers therein to the collection chamber at a point remote from said collection means, fiber opening means within said collection chamber in the path of the fibers carried in said airstream, means located above said opening means for introducing a binder to said fibers, and means for bypassing the airstream around said opening means while confining the fibers and binder to passage through said opening means.

4. An apparatus for collecting opened fibers in interfelted relationship comprising, a collection chamber, an air-pervious floor in said chamber, means for conducting an airstream carrying fibers therein to the collection chamber above said floor, fiber opening means within said collection chamber in the path of the fibers delivered in said airstream, means located above said opening means for introducing a binder to said fibers, means for bypassing the airstream around said opening means while confining the fibers and binder to passage through said opening means, and suction means below said floor.

5. An apparatus for collecting opened fibers in interfelted relationship comprising, a collection chamber, fiber collecting means in the chamber, a conduit having an exit opening in said chamber at a point remote from said fiber collecting means, card rolls within said collection chamber beneath said exit opening and closing off a portion of the cross-sectional area of said collection chamber, and air-pervious means closing off substantially the remainder of such area to permit an airstream to by-pass said card rolls while the fibers are confined to passage between said card rolls.

6. An apparatus for collecting opened fibers in interfelted relationship comprising, a collection chamber, an air-pervious conveyor in the chamber forming the floor thereof, a conduit leading to said chamber and having an exit port in a wall thereof remote from said conveyor, fiber opening roll means between said port and said conveyor, and means for withdrawing air through said conveyor.

7. An apparatus particularly adapted for felting mineral wool fibers comprising, a collection chamber, an air-pervious conveyor forming the floor of said chamber, means for establishing a negative pressure beneath said floor, means for conducting an airstream carrying fibers therein to the collection chamber at the upper part thereof, fiber opening rolls in said chamber in the path of fibers delivered in the airstream, an air-pervious member adjacent said rolls obstructing passage of fibers whereby fibers are caused to pass downwardly between said rolls, said member comprising a rotating perforated drum rotating toward the opening rolls.

8. Fiber collection means comprising a vertically extending tower, a fiber inlet in the top of said tower, means for delivering fiber through said inlet in an airstream, fiber opening means positioned beneath said inlet and located in the upper portion of the tower, a foraminous conveyor positioned beneath said fiber opening means and located at the bottom of the tower, and suction means for drawing air from the tower 20 through the conveyor.

9. The apparatus of claim 8 including means for introducing a powdered unset binder to said fiber in a region of the tower above said fiber opening means.

10. The apparatus of claim 9 including means for 25 introducing an adhesive spray to said fiber in a region of the tower below said fiber opening means.

11. A method of collecting fiber comprising carrying the fiber substantially vertically downwardly through an enclosed path, subjecting the fiber to an opening action at an upper portion of said path, forming an air suspension of the opened fiber, and collecting the fiber from the suspension.

12. The method of claim 11 including the step of introducing a powdered unset binder to the fiber prior to the opening action.

13. The method of claim 12 including the step of introducing an adhesive spray to the fiber subsequent to the opening action and while the fiber is in suspension.
